US00D872820S

(12) **United States Design Patent** (10) Patent No.: **US D872,820 S**
(45) Date of Patent: ** Jan. 14, 2020

(54) **DUAL-GRIP PORTABLE COUNTERMEASURE DEVICE AGAINST UNMANNED SYSTEMS**

(71) Applicant: **Battelle Memorial Institute**, Columbus, OH (US)

(72) Inventors: **Alexander Morrow**, Gahanna, OH (US); **Daniel E. Stamm**, Columbus, OH (US); **Raphael J. Welsh**, Powell, OH (US); **Daniel G. Loesch**, Columbus, OH (US); **Zachary Schmid**, Columbus, OH (US)

(73) Assignee: **Dedrone Holdings, Inc.**, San Francisco, CA (US)

(**) Term: **15 Years**

(21) Appl. No.: **29/680,172**

(22) Filed: **Feb. 14, 2019**

Related U.S. Application Data

(63) Continuation of application No. 16/274,325, filed on Feb. 13, 2019, which is a continuation-in-part of application No. 16/005,905, filed on Jun. 12, 2018, which is a continuation of application No. 15/596,842, filed on May 16, 2017, now Pat. No. 10,020,909, which is a continuation-in-part of application No. 15/274,021, filed on Sep. 23, 2016, now Pat. No. 10,103,835.

CLAIM

The ornamental design for a dual-grip portable countermeasure device against unmanned systems, as shown and described.

DESCRIPTION

FIG. 1 is a perspective view of dual-grip portable countermeasure device against unmanned systems.

FIG. 2 is a left side view thereof.

FIG. 3 is a front view thereof.

FIG. 4 is a rear view thereof.

FIG. 5 is a right side view thereof.

FIG. 6 is a top view thereof; and,

FIG. 7 is a bottom view thereof.

The broken lines of FIGS. 1-7 illustrate portions of the article and form no part of the claimed design.

1 Claim, 5 Drawing Sheets
